PAVEMENT FINISHING MACHINE

Erich H. Lichtenberg, Milwaukee, Wis., assignor
to Koehring Company, Milwaukee, Wis., a corporation

Application March 16, 1942, Serial No. 434,963

13 Claims. (Cl. 94—46)

The present invention appertains to the art of finishing machines of the type designed for finishing concrete aggregates deposited upon a subgrade of a road pavement, or the like.

It is customary for machines of the type, above generally referred to, to be supported at opposite sides of the subgrade being paved by means of road forms stationary upon the subgrade, the finishing machine being equipped with rollers or wheels to travel upon such forms.

The present invention involves certain improvements in spreading instrumentalities which are designed to mechanically spread batches of concrete aggregates deposited upon the subgrade, and further improvements involved herein relate to a screed unit of novel type for performing a finishing surface operation upon the aggregates after they have been spread upon the subgrade.

In certain types of finishing machines utilizing spreading mechanism for the purposes of this invention, the spreading means operates transversely of the roadway or subgrade being paved, and being driven by suitable power means, transverse forces, which are communicated to the spreading means, are transmitted to the road forms upon which the machine is mounted, tending to throw these forms out of alignment, and loosen them, in a disadvantageous manner for obvious reasons.

One of the primary objects of the present invention, therefore, has been to provide an endless belt or chain type of spreading mechanism in which the spreading devices are carried by oppositely moving sections or portions of the belt or chain means, which portions move in opposite directions transversely of the subgrade so as to neutralize the forces set up in their spreading action and prevent undue transverse stresses from being thereby communicated to the frame of the machine, and to the frame and supporting wheels and road forms.

A further object of this invention is to provide a novel arrangement of normally spaced spreading devices and disposition thereof with respect to moving means therefor, such as to permit a certain amount of the material being spread to flow between and past the spreading devices and to be finished off by any suitable auxiliary means adjacent thereto.

Still another object of the invention resides in the provision of peculiar means for vibrating or actuating the finishing screed provided as a part of the screed unit of the design of my machine of my improved finishing machine. The said

vibrating means is designed for operating the screed in a direction generally longitudinally of the road subgrade, as distinguished from the action of the spreading means transversely to said subgrade.

In addition to the longitudinal movement of the screed, above referred to, the actuating means causes the same to exert pressure forces downwardly and forwardly at an angle to the horizontal plane of the surface of the aggregates being emplaced on the subgrade. The action of the screed, as above described, affords a compacting of the road aggregates in a peculiar manner not heretofore achieved by previous types of means of this sort.

Generally speaking, a main object of my invention is to provide a machine comprising a novel spreading unit and a novel screed unit, the same assembled upon a main supporting frame for the machine and operable preferably from the same power plant.

Another object of this invention is to provide a novel arrangement of spreading instrumentalities associated with the spreading unit, novel drive means for the same and a novel arrangement of the parts involved in the device above mentioned.

A still further object of this invention is to provide a novel form of strike-off plate in which the members are individually adjustable to provide the crown contour for a road, or the like, and a further object of this invention is to provide a screed in which the vibratory action is a reciprocatory action in a substantially angular relationship with respect to the surface of the screed which contacts the concrete being finished.

Further and more particular objects of this invention will be set forth in the accompanying specification and claims, and referred to in the drawings, in conjunction with a description of the parts making up the machine shown in the drawings.

In the drawings:

Figure 1 is a side view of a machine of the character described, showing the arrangement of the spreading and finishing units in conjunction with a frame for supporting the same and drive means for operating the respective units and the machine. The said machine is shown as being supported in a travel position by road forms.

Figure 2 is a view taken about on the line 2—2 of Figure 1, looking in the direction of the arrows which illustrates the arrangement of the

sectional screed, and substantially indicates the vibratory member incorporated with said screed, including certain adjusting means therefor. Certain portions of the machine are broken away, and are illustrated further in other views.

Figure 3 is a fragmentary sectional view taken about on the line 3—3 of Figure 2, illustrating generally the adjusting means for the finishing unit and the individual adjusting means for the screed members, as well as the vibrating instrumentality associated with said members, the screed being raised from the road surface.

Figure 3A is a view taken about on the line 3A—3A of Figure 3, looking in the direction of the arrows, and illustrating certain particular features of the vibrating means.

Figure 3B is a sectional view with portions of the same broken away, illustrating certain guide means for the weight means and taken about on the line 3B—3B of Figure 3.

Figure 4 is a fragmentary view taken about on the line 4—4 of Figure 3, illustrating the sectional strike-off plate and certain adjusting means for the finishing unit.

Figure 5 is a sectional view, portions being broken away, taken about on the line 5—5 of Figure 3, and illustrating the adjusting instrumentalities for the screed and the relationship of the vibrating means to the same.

Figure 6 is a top view of the machine illustrated in Figure 1, generally diagrammatic in its showing, and illustrating primarily the driving instrumentalities for the respective spreading units and finishing units and the configuration of the spreading unit.

Figure 7 is a sectional view taken about on the line 7—7 of Figure 6, and illustrating the novel spreading instrumentalities of the spreading unit and certain adjusting means therefor.

Figure 8 is a fragmentary view with certain parts in section, of certain of the instrumentalities of the spreading unit clearly illustrating certain novel features therein.

Figure 9 is a fragmentary view taken about on the line 9—9 of Figure 8, looking in the direction of the arrows, and illustrating certain details of the spreading unit and the relationship of those details with one another.

Figure 10 is a sectional view taken about on the line 10—10 of Figure 9, looking in the direction of the arrows, with certain portions of the machine broken away, the said view illustrating certain of the spreading devices and the drive means therefor, in conjunction with guide means provided.

Referring generally to Figure 1, the machine to be described in this disclosure is shown as being comprised of a main frame A supported on a subgrade by means of the forms generally indicated B by conventional flanged wheels 1 adapted to roll over the forms and be guided thereby, the said main frame A having supported therein the spreading unit C adjacent the front of the frame A and rearwardly of the said spreading unit a finishing unit D, the said spreading unit, finishing unit and machine being propelled and the various units actuated by means of a power plant E located substantially above the previously mentioned finishing unit D.

Referring more particularly to Figure 6, wherein is shown the spreading unit C, previously mentioned, the main frame A is shown as having girder members or channel members forming a substantially rectangular lower frame portion, the longitudinal members of the frame

being denoted 2, and the transverse member indicated in the Figure 7 being denoted 3, suitable vertical frame members 4 supported on the frame members 2 and 3 in a conventional manner, and being connected thereto by welding or other suitable means, the said upright members 4 having connected at their upper ends longitudinal channels or beams 5 and a transverse beam 6 at the junction of the longitudinal beams 5 and the upright members 4. Spaced rearwardly of the front upright members 4 and completely within the main frame A is the sub-frame, generally denoted F, the same being a part of the spreading unit now to be particularly described in reference to Figure 7.

The sub-frame F is shown as having vertical channel members 7, suitably spaced within said main frame, and adapted to be fixed at the lower ends thereof to frame members 8, which may generally be channel members similar to the upright members 7, and the said frame members 8 and upright members are rigidly braced by means of cross braces 9 and 10, whereby a sub-frame F may generally be provided as a sort of depending frame from additional transverse girders or channels 10 suitably fastened at their ends to the longitudinal upper frame members 5, previously referred to in relation to Figure 1.

At this point reference is made to Figures 8 and 9 to indicate the structure of the sub-frame in somewhat more clear detail, the said frame members 8 being shown in these figures as having engaged at their outer ends bearing portions 12.

Referring back again to Figure 7, it will be seen that the frame members 8 are provided in pairs, whereby aligned bearings 12 are provided. The sub-frame F is formed in the manner above described in order to provide a framework for supporting endless chain means 13 thereon, by means of suitable sprockets 14, the said sprockets including bearing portions 15 adapted to rotate in the bearing members 12 affixed to the frame members 8, the said sprocket members 14 adjacent the upper and lower frame members 8 and at opposite ends being drivably interconnected by means of the chains 13, and the said respective upper and lower sprockets at each end of the frame F in turn being interconnected by means of shafts 16, the shaft 16 at one end of the spreader frame or sub-frame F, extending substantially above the transverse channel member 10 and being suitably carried in a bearing portion of a longitudinal bracing member 17, reference being here made at this point to Figures 6 and 7, the said shaft 16 having fixed at the outer end thereof a suitable pulley 18 adapted to be driven in a manner to be described.

Referring again to Figures 8 and 9, it should be mentioned that the sprockets 14, adjacent the ends of the upper and lower frame members 8, are adapted to coact with the chain members 13 in a manner that is apparent to those skilled in the art, whereby, when driving force is transmitted to the said sprockets, the chains will be carried around the sub-frame F in a conventional manner. The said chains 13, both the upper and lower chains, are rotated by the sprocket members 14 about the frame F in timed relation for reasons that will be apparent as the description of this machine progresses.

The purpose of the endless chains 13 will be apparent upon a consideration of Figure 10, wherein are shown the spreading devices adapted to be actuated by the chains, and which include

the paddle members 19 suitably fixed at the lower ends of the shafts 20. The said shafts 20 are adapted to pass through certain pivotal connections 21 of the said chains 13, whereby the same may be driven by the chains during the travel movement thereof, and at the same time, may be adjusted relative to said chains in a manner that is to be described.

Figure 9 shows that only certain of the said pivotal connections of the chains 13 are provided with the pivotal bearing members 21, the said bearing members being hollow to provide a bearing portion for the shaft 20, as previously mentioned, the ends of the additional links of the chain being connected together by generally conventional pivotal means 22.

Referring again to Figure 10, it will be seen that the paddle shafts are provided at their upper ends with crank members 23 formed integrally with said shafts, and at substantially right angles therewith, and at the outer ends of said crank members a further integral portion 24 is provided, adapted to carry guide rollers 25 thereon, adapted to coact with guide means 26 now to be described.

The guide means 26 comprises a channel member of a formation generally following that of the chains 13, and formed substantially as shown in Figure 10 with an up-turned lip 27 about its inner periphery, whereby the roller members 25 may contact the same with rolling contact during the travel of the chains 13 around the sprockets 14, carrying with them the shafts 20 upon which the crank arms 23 are provided, the said guide means 26 being adapted to be raised and lowered by suitable screw means 28 adapted to engage with ears or extensions 29 suitably fastened at the transverse extremities of said guiding channel 26. The said screw means 28 are carried in bearing portions 30 suitably fixed to the longitudinal channel members 5, previously referred to, collars 31 being provided on said screw means. The screw means 28 are provided at their upper ends with beveled gears 32 adapted to coact with corresponding beveled gears 33, suitably fastened on a transverse shaft 34, the said transverse shaft being carried by the longitudinal upper frame members 5 in bearing portions 35 fastened thereto, at its outer ends, and intermediate the said outer bearing portions 35 are additional bearing means 36 on extensions of the upright sub-frame members 7.

Adjacent one end of the transverse shaft 34, just referred to, a suitable crank 36a is provided, whereby raising and lowering movement may be imparted to the guide means or channel member 26, to thereby raise and lower the paddles or spreading devices 19. The raising and lowering of the spreading devices is effected by raising and lowering the shafts 20 to which the same are connected, the said shafts 20 being slidable in the bearing pivots 21 of the actuating chains 13, previously mentioned.

The paddle members 19, adjacent the lower ends of the shafts 20, are fixed to said shafts at an angle therewith, whereby when movement is imparted to the chains 13, the said paddles will be carried along with said chains, and move endlessly about the sprockets 14. The paddles, of course, are adapted to spread concrete or the like, when the said concrete is placed on a sub-grade, and the purpose of providing endless chains with paddles operating in opposite directions is to neutralize the shifting tendency nor-

75 mally provided in spreading devices operating in one direction transversely of a subgrade.

It will be apparent that the spacing of the paddles 19 permits the flow of concrete aggregates therebetween while spread thereby, and then move past the same and directly to the oppositely moving paddles, whereby the latter will also spread part of the mix and overcome the tendency of the machine to shift in either direction incident to stresses set up by action of the paddles on the aggregates. This will facilitate a rapid spreading, since as the machine moves forwardly, the paddles may be moved by the chains at an increased speed as compared with a construction whereby only the front lap and paddles moved thereby are used to accomplish the spreading action.

It is pointed out that the paddle members 19 are so actuated as to spread certain portions of a mass of concrete deposited on a subgrade, transversely of said subgrade, whereby pressure forces, exerted on the sub-frame and consequently on the main frame, are neutralized. The said pressure forces, normally being transferred to the flanged machine supporting wheels 1, and in turn, to the road forms B over which the supporting wheels 1 travel, it will be seen that these pressure forces are neutralized, since the opposite laps of the chain 13 proceed in opposite directions and bear the paddle members or spreading devices 19 in opposite directions.

The crank members 23, on the spreading device shafts 20, are provided to maintain the angular relationship shown in Figure 9, of the respective spreading devices 19, during their travel as carried by the chains 13. It is, of course, apparent that these spreading devices 19 may be fixed to the shafts 20 in any desired angular relationship therewith, to effect the spreading operation desired. The desirability of providing adjustable spreading devices is obvious, since, under many conditions, the depth to which the spreading devices are to penetrate into a mass of concrete being spread, thereby, must be different as the concrete is laid in increasing thickness upon the subgrade. It is likewise desirable to drive these adjusting means in a simple manner, and provide them of a simple form, and to carry the spreading devices and the chains and sprockets which drive the same on a rigid framework to more effectively accomplish the spreading of concrete, or the like.

Referring now to the finishing unit D, previously mentioned in connection with the description of Figure 1, it will be seen that the said unit is located and supported on the main frame A rearwardly of the spreading unit C, just previously described. The finishing unit D is supported on the main frame A in a manner whereby the same may be adjustable vertically in accordance with necessary conditions, the said finishing unit D comprising generally a rectangular upper frame G, which includes longitudinal frame members 37 adjacent the longitudinal main frame members 5, and transverse frame members 38 integrally connected with the said longitudinal frame members 37 at the ends thereof.

Reference at this point is made to Figure 3, wherein the transverse frame members 38 are shown as being provided with rearwardly and forwardly projecting members 39. A screed, generally indicated H, is provided for the finishing unit D, the screed being made up of sectional members 40, having hinge portions 41 at the edges thereof, the said hinge portions being con-

nnected together by pins, the individual screed members being formed substantially as shown in Figure 3, with upwardly extending edges 42 at the front and rear edges of the said screed members 40, the said up-turned edges 42 in turn having 5 rigidly connected thereto, inwardly extending flanges 43, adapted to be engaged by supporting adjusting bolts 44. The said adjusting bolts 44 are vertical members and are provided at their lower ends with threaded portions adapted to be 10 engaged by nuts 45 having semi-circular faces.

Upon consideration of Figure 5, it will be noted that the semicircular faces of the nuts above and below the flange portions 33 are opposed, whereby a rocking bearing connection is provided, it being 15 apparent that the flange portions 43 are furnished with suitably reamed out openings to be engaged by the supporting rods 44 and nuts 45. The upper ends of the supporting rods 44 are similarly provided with semicircular nut members 45 adapted to be screwed onto threaded portions of the supporting rods and into engagement with the members 39, previously referred to, to provide upper supporting bearing members. Between the upper nuts 45 and the upper surface of member 39, surrounding the rods 44, coil springs 44a are 20 furnished to facilitate the finishing action of the screed in a manner that will be understood as the description progresses.

At this point, Figure 5 is referred to, to illustrate a certain adjusted position of the interconnected screed members 40, by means of the supporting rods 44, just referred to, it being well known that under many conditions a crowned surface of a concrete road is desirable, the same being possible of attainment by a screed such as that illustrated in the said Figure 5.

The structure provided, heretofore described, is thus seen to be essentially an adjustable swingable structure, adapted to be reciprocated at a high rate of speed, by means of a novel form of vibrating mechanism now to be described, and in a novel manner. While only one of these vibrating units is shown, it is apparent that under certain conditions a plurality of the same may be provided affixed to the individual screed members to operate the screed. Referring more particularly to Figure 3 again, it is seen that a vibrating member, generally denoted J, is comprised of a plate member 46 affixed at its lower edge to the upper surface of one of the screed members 40, in a conventional manner, and a rear plate member 47 similarly affixed to said screed member and substantially parallel with the first named plate member.

An angularly inclined bottom member 48 is provided suitably connected at its rear edge with the rear plate member 47, and at its forward or front edge to the upper surface of the screed member 40, the said angularly inclined member 48 providing a surface over which a weight 49, more clearly illustrated in Figure 3B, is adapted to be reciprocated.

The weight 49 is confined for travel movement between flanges 50 suitably fixed to the inclined member 48 and including tongues 51 adapted to coat with corresponding grooves 52 of the said weight 49, whereby the said weight may be moved in a manner to be described. The weight 49 is provided with a transverse elongated slot 53 adapted to be engaged by the lower end of a crank member 54a, the said crank member 54a being carried by an angularly inclined plate 55 parallel with the previously referred to plate 48, the said plate 55 providing a bearing for a portion of said

crank member 54a, an additional bearing member being provided in a plate 56, whereby the crank shaft 54 may be rotated in a manner to be described.

Adjacent the outer end of the crank shaft 54 is provided a beveled gear 57 adapted to be rotated by means of another bevel gear 58, the bevel gear 58 being in turn supported by means of a drive shaft 59 engaged in bearing members 60 of the front and rear plate members 46 and 47, the said drive shaft 59 carrying at its outer end a pulley 61, adapted to be rotated therewith by drive means to be described later.

It will be seen that when the bevel gear 58 is rotated, similar motion will be transferred to the crank shaft 54, and the crank portion thereof, engaged with the slot 53 in the weight 49, will cause the said weight to reciprocate angularly with respect to the screed member 40, and impart thereto angular movement, whereby the said screed member 40 will be vibrated in a substantially downward and forward direction to thus transfer to the concrete contacted by the said screed members 40, a compacting action.

Since the respective screed members 40 are integrally connected, the screed H, as a whole, will be moved in a unitary manner to impart the compacting action over the surface of the road, to thus effectively accomplish the finishing of the said road in a desirable manner.

The front transverse member 38 of the supporting frame G is provided adjacent its lower portion with a flange 62 depending therefrom, adapted to support strike off members 63 more particularly illustrated in Figure 4, whereby the said members 63 may be adjusted relative to the frame member 38 by means of suitable nut and bolt means 64 engaging elongated slot portions 65 of said strike-off plate members 63. As will be readily understood, the strike-off plate members generally provide a single strike-off plate in effective action, which plate may be adjustably disposed with respect to the desired crown of a road being finished by the machine under discussion.

Since the crown formation of various roadways may be desirably different, the reason for this adjustable feature of the strike-off plate is readily apparent. Since the strike-off plate is supported on the frame G, it will be noted that the vertical adjustment of the said frame G will carry with it the said strike-off plate. The vertical adjustment is effected by means of screw members 66 properly disposed with respect to the longitudinal frame members 37, adapted to contact with threaded portions therein, the said screw members 66 being in turn borne by projections 67, the said projections 67 being suitably fastened to the main frame A in any conventional manner, the pairs of the adjusting screw members at opposite

60 sides of the frame being adapted to be operated in unison by means of shafts 68 carrying at their ends suitable beveled gears 69 adapted to coat with mating bevel gears 70 keyed to the screw shafts 66, previously mentioned, the said shafts 68 being carried on supports 71, the said supports being fastened to the main frame A in any conventional manner. In order to move the adjustable frame G as a unit, the adjusting shafts 68 at each side of said frame are adapted to be operated by means of a chain 72 connecting the said shafts 68 operatively, by means of gears fixed to said shafts. A suitable drive gear 73 is supported on a shaft 74 of bearings 75, the said bearings 75 being carried by transverse frame members 76, the said gear 73 being driven by means of a belt

71, drivably connected with a pulley 78 operated by the motor or power plant E, through a shaft 79. In order to transfer power for reciprocating the weight 49 of the vibrating mechanism J, previously referred to, a power shaft 80 driven from the motor E, see Figure 1, is provided, and at its outer end carries a pulley 81 adapted to operate a belt 82.

Referring at this point to Figure 5, it will be seen that this belt 82 drives a pulley 83 suitably fixed to a vibrator drive shaft 84, the said vibrator drive shaft 84 being carried by bearing members 85a on the transverse members 38 of the adjustable frame G, previously referred to. The vibrator drive shaft 84 is provided with a pulley 85 adapted to operate a belt 86, the said belt 86 being preferably a V-belt, which belt 86 is engaged with the pulley 61 of the vibrator mechanism J, previously referred to.

To provide for the adjustment of the screed members 40 of the screed unit H, it is necessary to provide means for maintaining tightness of the belt 86 for driving the vibrating device J, and there is shown suitable belt tightening means generally indicated 87, of any conventional form, the said tightening means being seated adjacent the upper ends of the supporting rods 44 of the screed members on a projection of the member 39 engaged by said rods 44.

It will thus be apparent that a suitable drive has been provided to actuate the vibrator unit J, under all adjusted conditions of the screed H. The screed H may be in turn raised as a whole by means of the raising of the frame G supporting the said screen, through the instrumentalities previously referred to, namely, the screw members 66 operated in the previously described manner.

It is, of course, believed clear that the strike-off plate members 63 will be correspondingly raised and lowered when the finishing unit D is raised and lowered, as previously described. The novel vibrating means effects a complete compacting action of the concrete being operated on in an entirely new manner. Since previously the vibrating action has either been effected in a manner parallel to the surface of the material being compacted, or in a vertical manner, the vibrating action effected by the finishing unit, just described, will be seen to be a component of these two actions, and as such, combines the desirable qualities which each may have and eliminates certain undesirable reactions obtained in previous devices.

The main frame A may be driven or moved over the road forms on the wheels 1, by suitable chain means 88, driven by suitable gearing 89 operated by the motor E, the said gearing 89 effecting this operation by means of a transverse shaft 90 suitably carried in bearing members 91 on the main frame A, the said shaft 90 including gears 92 at its outer ends for engagement with the chains 88, the chains 88 in turn being engaged with gears 93 suitably keyed to the wheel supporting shaft 94, whereby the machine may be operated.

It is understood that the drive for the spreading unit C is effected by means of a shaft 95 driven by the power plant E, and the said shaft 95 is provided at its outer end with a bevel gear 96 adapted to coact with a bevel gear 97 on a shaft 98, the said shaft 98 in turn having engaged near its lower end, a pulley 99. The pulley 99 is adapted to operate a belt 100, the said belt 100 in turn being carried by the pulley 18 ad-

jacent the upper end of the drive shaft 16 of said spreading unit.

It should be understood that the vibrating action of the screed is effected longitudinally of the road subgrade and of the material being compacted, and as such, is at an angle to the spreading action effected by the spreading unit C, previously referred to, whereby the stability of the main frame A is maintained throughout the spreading and finishing action. A notable feature of the construction of the spreading unit, is the advantage derived from being able to move portions of a concrete mass intact without danger of separating the ingredients of the mixture being spread.

Having thus described my invention, what I claim as new and desire to secure by Letters Patent of the United States, is:

1. A finishing machine of the class described, in combination, a main frame, a spreader unit comprising transverse endless belt type spreader means including spreading devices carried by spaced front and rear belt laps, said belt means disposed in a plane above the spreading devices and the latter being adapted to spread a mass of concrete deposited on a subgrade, supporting means for the endless belt means providing an uninterrupted passage space for the spread concrete to pass between and from the spreading devices of the front lap of the belt means to the spreading devices on the rear lap of the belt means, means to actuate said devices so those in front and in rear move in opposite directions transversely of the subgrade and relatively to each other, whereby the pressure forces exerted on said frame during the spreading operation are partially neutralized, and a finishing unit supported on said frame, rearwardly of said first named unit, including a screed, and means for imparting a reciprocatory angular movement to said screed longitudinally of the subgrade to thereby compact a mass of concrete spread by said spreader unit.

2. A finishing machine of the class described, in combination, a main frame movable over a subgrade, wheel means for said frame, road forms on the subgrade forming track members for said wheel means, operating means on said frame, a first transverse sub-frame adjacent the front of said main frame, comprising a spreading unit vertically adjustable relative thereto, including endless belt spreading means, associated with said sub-frame, spreading devices operable by said belt in opposite directions, and movable in a plane wholly below the belt so that the concrete spread by front spreading devices may pass directly to and be spread by rear spreading devices traveling in an opposite direction, the pressure forces tending to shift the wheels and thereby misalign the road forms being partially neutralized by the pressure forces exerted in opposite directions by the spreading devices during the spreading operations, and a second sub-frame rearwardly of said first mentioned sub-frame, said second sub-frame including means for vertically adjusting the same and comprising a finishing unit having a screed member, and a strike-off plate, said strike-off plate operable to level a mass of concrete spread by said spreading unit, and said screed member including means for imparting a reciprocatory vibrating movement to the same longitudinally of the subgrade whereby the pressure forces exerted on the main frame and the wheels are at substantially right angles to the partially neutralized pressure forces exerted on

said frame and wheels by said spreading unit, the said frame and wheels thereby remaining in a substantially stabilized condition.

3. In a finishing machine of the class described, in combination, a frame, endless belt type spreading means for spreading a mass of concrete, comprising a spreader unit associated therewith including spaced apart spreading devices operable in one direction and other spreading devices adjacent said first mentioned devices operable in another direction, mounting means wholly above and for supporting the front and rear spreading devices providing a space between them in the direction of forward movement of the machine and through which space portions of the mass may pass directly from the front devices rearwardly to the rear devices, whereby pressure forces exerted on the frame tending to shift the same are partially neutralized during the spreading operation, the spacing of said first mentioned spreading devices being such that part of the mass of concrete deposited adjacent thereto may flow between and past the same directly to the said other spreading devices and be spread thereby.

4. In a finishing machine of the class described, in combination, a frame, endless belt type spreading means for spreading a mass of concrete, associated therewith, comprising endless chains, spaced apart spreading devices operable by said chains in one direction, and other spreading devices operable in an opposite direction, mounting means wholly above and for supporting the front and rear spreading devices providing a space between them in the direction of forward movement of the machine and through which space portions of the mass may pass directly from the front devices rearwardly to the rear devices, whereby pressure forces tending to shift the frame in either direction during the spreading operation are partially neutralized, the spacing of said first mentioned spreading devices being such that part of the mass of concrete being spread may flow between and past the same and be spread by said other spreading devices.

5. In a finishing machine of the class described, in combination, a frame, endless belt type spreading means for spreading a mass of concrete, associated therewith, comprising front and rear devices for successively acting on and spreading portions of said mass in opposite directions, mounting means wholly above and for supporting the front and rear spreading devices providing a space between them in the direction of forward movement of the machine and through which space portions of the mass may pass directly from the front devices rearwardly to the rear devices, and a single continuous endless drive means engaged with said devices and wholly above them, whereby the pressure forces exerted on said frame by said devices during the spreading operation are partially neutralized.

6. In a finishing machine of the class described, in combination, a frame, drive means on said frame, endless chains associated with said means, spaced front and rear paddle spreader members movable by said chains in opposite directions for spreading concrete or the like, pressure forces exerted on the frame by the spreader members moving in one direction being partially neutralized by the pressure forces exerted on the frame by the members moving in the other direction during the spreading operation, mounting means wholly above and for supporting the front and rear spreading members providing a

space between them in the direction of forward movement of the machine and through which space portions of the mass may pass directly from the front members rearwardly to the rear members, and guide means for said spreader members separate from said endless chains adapted to maintain the members in a predetermined angular relationship with respect to said chains, said mounting means being disposed in a plane wholly above the spreader members.

7. A machine as claimed in claim 6, wherein the guide means is vertically adjustable to raise and lower the paddle spreader members.

8. In a finishing machine of the class described, in combination, a frame, drive means on said frame, endless chains associated with said means, spaced front and rear paddle spreader members movable by said chains in opposite directions for spreading concrete or the like, pressure forces exerted on the frame by the spreader members moving in one direction being partially neutralized by the pressure forces exerted on the frame by the members moving in the other direction during the spreading operation, mounting means wholly above and for supporting the front and rear spreading members providing a space between them in the direction of forward movement of the machine and through which space portions of the mass may pass directly from the front members rearwardly to the rear members, and guide means for said spreader members separate from said endless chains adapted to maintain the members in a predetermined angular relationship with respect to said chains, said mounting means being disposed in a plane wholly above the spreader members, the paddle spreader members including shafts slidably supported in pivots of the endless chains, the said shafts engaged with the guide means by crank portions, and the guide means being vertically adjustable to raise and lower the spreader members with respect to the chains and concrete or the like being spread.

9. The combination of a finishing machine of the class described having a main frame, track engaging wheels supporting the same for travel movement over a subgrade, and road forms on the subgrade comprising tracks for engagement by the wheels aforesaid, and transverse endless belt type spreading means supported by the frame, including endless chains spaced above and carrying spaced front and rear spreader members in opposite directions, for spreading concrete deposited on the subgrade, transversely thereof, a part of the concrete deposited adjacent the spreader members moving in one direction flowing therebetween and past the same being spread by the spreader members moving in the other direction, the pressure forces exerted on the frame by the oppositely moving spreader members being substantially equalized whereby transverse shifting of the wheels and road forms is obviated, mounting means for supporting the front and rear spreading members providing a space between them through which portions of the mass may pass directly from the front members rearwardly to the rear members.

10. The combination of a finishing machine of the class described including a main frame, track engaging wheels supporting the same for travel movement over a subgrade, means for effecting said travel movement, and road forms on the subgrade having track portions thereon for engagement by said wheels, endless belt type spreading means including endless chains carry-

ing spaced front and rear spreader members movable in opposite directions, supported by said frame, mounting means for supporting the front and rear spreading members providing a space between them through which portions of the mass may pass directly from the front members rearwardly to the rear members, the said spreader members adapted to spread concrete or the like deposited on the subgrade in opposite directions whereby during travel movement of the machine part of the concrete deposited on the subgrade will flow between and past the spreader members moving in one direction and be spread by the members moving in the opposite direction.

11. In a finishing machine for concrete pavement construction, in combination, a support, drive mechanism for advancing the support over a subgrade upon which concrete aggregates are deposited to form the pavement, spreading mechanism comprising a series of separate front and rear spreader members spaced apart from each other to enable the aggregate materials to pass the front spreader members to the opposite rear spreader members, means above the spreader members connecting the spreader members to the support such that the spaces between the spreader members are unobstructed sufficiently that the aggregates being spread may pass into and through the spaces aforesaid as the members spread the aggregates during the forward movement of the machine, and means for moving the front spreader members in one direction and the rear spreader members in an opposite direction and all the spreader members at an

angle to the direction of movement of the machine during their spreading operation.

12. In a finishing machine of the class described, in combination, a frame, means to move said frame forwardly, spreading means carried by the frame including front and rear spaced apart spreading devices for spreading a mass of concrete deposited on a subgrade, the spaces between said front and rear devices being sufficiently unobstructed such that at least part of the mass of concrete so deposited will pass from advanced portions of said devices between the devices and past the opposite portions thereof during the forward movement of the frame and spreading operation, and means connecting the spreading devices to the frame located so as to provide the unobstructed spaces between front and rear such members.
13. In a finishing machine of the class described, in combination, a support, means to move the support forwardly, spreading means associated with the support including spaced front and rear paddle spreader members for spreading a mass of concrete deposited on a subgrade, the space between said members being such that at least a portion of the mass of concrete deposited on the subgrade will pass from advanced members to the rear members through the said space between the same, and past the said members, and means connecting the spreading devices to the frame located so as to provide the unobstructed spaces between front and rear such members.
